UNITED STATES PATENT OFFICE.

EUGENE C. WAMELINK, OF CLEVELAND, OHIO.

PNEUMATIC PIANO-PLAYER.

1,210,239.

Specification of Letters Patent. Patented Dec. 26, 1916.

Application filed April 24, 1909. Serial No. 491,884.

To all whom it may concern:

Be it known that I, EUGENE C. WAMELINK, a citizen of the United States, residing at Cleveland, in the county of Cuyahoga and State of Ohio, have invented certain new and useful Improvements in Pneumatic Piano-Players, of which the following is a specification.

This application relates to improvements 10 in piano players generally and represents a modified arrangement and construction over that shown in my copending application Serial No. 486,372 filed March 29, 1909 wherein the power pneumatic, controlled in 15 the usual manner by the secondary pneumatic which is under the control of the primary pneumatic and receives its actuation through the medium of the admission of tracker board air, is governed in its operation 20 by a device which receives its actuation from the tracker board air also and the intensity, or the volume of sound, produced by the power pneumatic is dependent at all times upon the volume of air admitted from 25 the tracker board so that if the music sheet is provided with perforations of greater width for the melody or theme the power pneumatic operated through the instrumentality of the admission of air through these 30 perforations will produce tones which are increased in volume over the tones of the accompaniment and the theme of the piece is brought out in just the manner in which it would be brought out by a master or by 35 the original composer. While the present invention is a modification of the construction set forth in such application and may or may not be more effectual in bringing about the results pointed out in such previous 40 application, it comprehends a construction and arrangement which is highly effective in operation. Then too the present invention contemplates addition of other features to be more fully disclosed.

45 In piano players generally there has been at all times a great desire to arrange the mechanism in a manner such that the bass notes are spoken with an increased intensity, or volume of sound, over that of the treble and this is usually brought about, in machines already in use, by means of suitable controlling buttons and devices which intensify, as it were, the operation of the actions for the bass so that the operator 50 may cause them to be played heavier than the treble or with more intensity than the

treble, but here again we meet the great stumbling block that, as a rule, the user of a piano player is unskilled in the art of music and does not appreciate the importance or the value of such a manipulation so that if the machine itself would automatically control such features, and would intensify the bass notes, the music rendered by the instrument would be much better in 60 point of technique and a long-felt want would be accomplished.

This invention, therefore, relates to a piano player action of the pneumatic type wherein the tracker board supplies its air 70 to the primary pneumatic which in turn, when operated, supplies air to the secondary pneumatic, this pneumatic being adapted to open up the port leading to the power pneumatic and permit the suction to act upon 75 this element in the production of the tone, together with a suitable device acting directly upon the vacuum valve controlling the communication between the power pneumatic and the vacuum chest and regulating 80 the extent of its opening in direct proportion to the volume of air admitted from the tracker board.

Invention further resides in the arrangement of a suitable control for the bleed between the tracker board air line and the vacuum chest whereby the effective operation of the controlling device, acting on the vacuum valve, is regulated to a nicety so that a machine equipped with actions of this 90 character might be set so that the bass notes will be spoken with greater intensity and volume than the treble.

Invention still further resides in a novel arrangement of the vacuum valve and relief valve whereby after the power pneumatic has operated, and assumes normal position, the relief valve is re-seated so that upon the next operation of the action the outside air or relief valve need only be held closed. 95 Thus it will be seen that the power pneumatic will be operated instantly upon the opening of the vacuum valve which up to the time of operation has cut off any communication between the vacuum chest and the power pneumatic.

Invention still further resides in certain details of construction and combinations of parts hereinafter set forth in the following description, drawing and claims.

110 Referring to the drawing, the figure represents an action in section to show the

parts thereof, and connected to the tracker board which is shown in connection with a sheet of music having different sized openings or perforations therein.

5 In carrying out the invention any preferred form and construction of parts may be employed so long as they possess the necessary features, but I have shown one construction in the drawings which meets 10 the requirements very effectively, and in such embodiment 1 represents the tracker board provided with the usual openings 2 permitting the admission of outside air to the tracker board air tubes 3. Coöperating 15 with this tracker board is a music sheet 4 having one size of perforations 5 and wider perforations 6 all for a purpose to be described.

Each pneumatic action for each piano 20 abstract comprises a power pneumatic 7 secured to the casing 8 and communicating by an opening 9 with an opening 10 which is in communication with an opening 11 extending to a vacuum chamber 12 which is 25 connected by suitable openings 13 with the secondary vacuum chamber 14 in open communication with the exhaust opening 15. Secured to the inner wall of the chamber 12 about the opening 11 is a valve seat member 30 16 provided with a valve seat 17 having secured thereto a leather washer 18 which receives upon it a vacuum controlling valve 19 of any preferred construction. The vacuum valve controls the exhaust of the 35 power pneumatic as will appear. This valve 19 is secured to the end of a sleeve 20 which has rigidly secured to it a diaphragm 21, the edge of which is secured to the partition 12'. The sleeve 20 extends through a 40 suitable opening in the partition 12' and has secured to the end thereof a diaphragm 22 which is secured at its edge to the partition.

Slidably mounted within the sleeve 20 is 45 a relief valve rod 23 having upon the left end thereof as shown in the drawing, a button 24 adapted to be engaged by the secondary pneumatic diaphragm 25, which is secured at its edge to the inner wall of the 50 casing within the secondary vacuum chamber 14. A suitable opening 26 is formed in the casing back of this diaphragm to provide clearance for the action of the air upon the diaphragm. A port 27 is arranged in 55 the casing and passes up to the top thereof for a purpose to be later described. The rod 23 is provided between the button 24 and the diaphragm 22 with a button 28 having thereon a suitable leather or other washer 60 29 adapted to seat against the end of the sleeve and form a seal between the secondary vacuum chamber 14 and the opening about the rod 23 within the sleeve 20. The end of the rod 23 opposite to the button 24 65 is provided with an outside air or relief

valve 30 which is rigid upon the rod and is adapted to seat against the casing about an opening 31 formed therein and establishing communication between the opening 10 and the outside air. A strip 32 may be secured to the outside of the casing and may be provided with an opening for guiding the rod 23. A spring 33 is arranged between the vacuum valve 19 and the outside air valve 30 and the normal tendency of this spring is to shift the latter yieldingly against its seat and to hold the rod normally in the position shown in the drawings with the button 24 away from the secondary pneumatic diaphragm 25, and further to hold the 70 vacuum controlling valve against its seat with the diaphragms 21 and 22 flexed to the left as shown. The partition 12' is provided with suitable clearance space 34 behind the diaphragm 21 and this space 75 communicates by a suitable opening 35 with a pipe 36 connected to a pipe 37 leading to the tracker board air tube 3. A suitable bleed 38 is arranged between the opening 35 and the vacuum chamber 12 whereby 80 the vacuum is equalized on both sides of the diaphragm 21 and in the tracker board air line.

The primary pneumatic device comprises a suitable casing 39 secured to the casing 8 and having therein a primary vacuum chamber 40 provided with an opening 41 leading to the outside of the casing. Slidably mounted in this opening 41 is a valve stem 42 having upon the upper end thereof a valve 43 and upon the lower end thereof a valve 44. These two valves are separated sufficiently so that when one is closed the other is open, and the stem 42 is of sufficient size such that air may pass around it. The opening 41 is in open communication with an opening 45 connected to the port 27 leading to the space behind the secondary pneumatic diaphragm.

Secured in the lower valve 44 is a stem 46 secured in a button 47 which is adapted to be acted upon by a primary diaphragm 48 secured at its periphery to the inner wall of the casing. Suitable clearance space 49 is provided back of this diaphragm and an 110 opening 50 leads from this clearance space to a tracker board air pipe 51 secured in the primary pneumatic casing 39 and connected to the tracker board air pipe 37.

Let us assume that the machine is at a 115 state of rest as is shown in the drawings and that a suitable vacuum is being created in the vacuum chambers 12 and 14 through the opening 15, then there will be a vacuum acting upon the vacuum controlling valve and tending to hold it closed against its seat. The same force will be acting through the port 40' in the chamber 40 of the primary pneumatic casing and will be drawing the valve 43 down upon its seat and will be acting further 120

through the bleed 38 upon the tracker board air line and upon the underside of the primary pneumatic valve as well as upon the left side of the secondary pneumatic diaphragm causing them to assume the position shown. Now as an opening in the sheet of music is presented to one of the openings 2 in the tracker board atmospheric air is supplied through the pipe 37 to the under side 10 of the primary pneumatic diaphragm 48 with the result that it will move upward due to the vacuum in the chest 40 with the result that the valve 44 is closed and the valve 43 is open, thus admitting outside air 15 around the stem 42 and permitting it to pass freely through the opening 45 to the port 27 and upon the left side or back of the secondary diaphragm 25 which will result, in a well known manner, 20 in the relief or outside air valve being forced tightly upon its seat and preventing the admission of air at this point. In the meantime, however, tracker board air is passed through the pipe 36 through the 25 opening 35 to the clearance space 34 behind the diaphragm 21 and through the opening in the partition about the sleeve 20 to the clearance space behind the diaphragm 22, but since the diaphragm 21 is larger in 30 area than the diaphragm 22, the sleeve 20 will be shifted to the right, thus opening the vacuum controlling valve 19 and permitting the air in the power pneumatic to be drawn therefrom through the connecting 35 openings 9 and 10, thus producing the operation of the power pneumatic. When the opening in the music sheet has passed beyond the opening in the tracker bar, the primary valve returns to its normal position, as shown in the drawing, 40 when the valve 44 will permit the vacuum to act through the port 41 and channel 45 to exhaust the air from the secondary pouch when the outside air valve 30 will be 45 released and outside air will rush into the power pneumatic to release the same. In the meantime, however, atmospheric air which passed into the channel 35 behind the vacuum controlling valve pouch 21, is being 50 exhausted through the bleed 38 when the vacuum will draw the vacuum controlling valve 19 down upon its seat. The adjustment of the vacuum controlling valve and the valve 30 is such that when the action 55 is inactive both valves are seated, but during the release just described and after operation, the valve 30 is moved back against the tension of its spring 33 by atmospheric air flowing in to relieve the power pneumatic which returns to normal position.

It will be seen that if the opening in the sheet of music be varied then the volume of tracker board air admitted will be varied, and the extent of flexing of the diaphragm 60 21 to the right will be varied also, with the

result that the extent of opening of the valve 19 will be varied so that the force exerted by the power pneumatic will be greater or less according to the opening of the vacuum valve. The force of the stroke of the power 70 pneumatic therefore is always commensurate with the volume of air admitted from the tracker board. With this construction and arrangement in mind, let us assume that all the notes of the accompaniment of any 75 composition be designated by one size of openings and the melody or theme be designated in the same sheet of music by openings or perforations of an increased width over those of the accompaniment, then the 80 power pneumatics of those actions, corresponding to the theme or melody, will produce an intensified stroke or intensified tone, and the theme or melody of the piece will stand out above the accompaniment. 85

In order to vary the effective operation of one pneumatic action relative to all of the rest or to arrange a series of pneumatic actions in a manner such that they will operate with greater or less force relative to the rest, a regulating valve 52 is screwed into the casing and is adapted to regulate the flow of air through the bleed 38, and by adjusting this valve and cutting down or increasing the flow of air through this bleed, 90 the operation of the entire action is intensified or is varied so that even with the ranges of operation caused by varying volumes of air admitted from the tracker board the operation of one pneumatic action may be 100 varied with respect to the rest, so that if it is desired to intensify the tones of the bass, this may be accomplished by regulating these valves to diminish the flow through the bleed of each pneumatic for the bass so 105 that the vacuum may operate these pneumatics with greater force than the actions which correspond with the treble.

Having described my invention, I claim:

1. In a player action, a tracker bar, means whereby the effective opening to each tracker duct may be independently varied, a power pneumatic for each tracker opening, a vacuum chest having communication with each power pneumatic, vacuum valve mechanism for each power pneumatic and controlling the exhaust of the same, motor means for actuating said valve mechanism and actuated by air admitted through the corresponding opening in the tracker, and means for governing each vacuum valve mechanism to cause it to control the exhaust of its corresponding power pneumatic in direct accordance with the volume of air admitted to the corresponding opening in the tracker. 110

2. In a pneumatic piano player, in combination, a tracker board, a power pneumatic, a vacuum chest, said power pneumatic and said chest being connected by a 115 120 125

suitable opening, a single device in said opening for controlling the exhaust of the power pneumatic, motor means therefor having a variable operation according to the 5 volume of air admitted from a corresponding single opening in the tracker, and means for varying the volume of air admitted by the tracker board to each action and independently of the vacuum in the player.

10 3. In a piano player action, in combination, a power pneumatic, a vacuum chest, said parts being connected by a suitable opening, a single valve for controlling the exhaust of the power pneumatic, motor 15 means connected to a single opening in the tracker for controlling said valve and for actuating it varying amounts in accordance with variations in the volume of outside air admitted at the corresponding opening in 20 the tracker, and means for varying the volume of air admitted at such single opening and independently of the vacuum in the chest.

4. In a piano player, in combination, a 25 tracker board, a power pneumatic, a vacuum chest, said power pneumatic and said chest being connected by a suitable opening, a single vacuum valve for controlling said opening, an outside air valve free to open 30 and permit the power pneumatic to assume normal position, means for closing the outside air valve upon the operation of the action, motor means for operating the vacuum valve and connected to a single opening in 35 the tracker and varying in its operation with the volume of air admitted at the corresponding single opening in the tracker, and means for admitting varying volumes of air to the several openings in the tracker 40 board independently of the vacuum in the chest.

5. In a piano player, in combination, a tracker board, a power pneumatic, a vacuum chest, said power pneumatic and said chest 45 being connected by a suitable opening, a single valve for closing such opening, an outside air valve for admitting outside air to the power pneumatic to permit it to assume normal position, means actuated by 50 the admission of air by the tracker board for holding said outside air valve closed, a motor device connected with the single opening in the tracker and varying in its operation with the volume of air at the corresponding single opening in the tracker, and means for varying the volume of outside air admitted by the tracker to such device.

6. In a piano player, in combination, a 60 tracker board, a power pneumatic, a vacuum chest, said power pneumatic and said chest being connected by a suitable opening, a single vacuum valve for closing said opening, an outside air valve, a secondary pneumatic for holding said outside air valve 65

closed, a pneumatic device for operating the vacuum valve and connected with a single opening in the tracker and varying its operation with the volume of air admitted at the corresponding single opening 70 in the tracker, and means for varying the volume of air admitted to each single opening in the tracker independently of the vacuum in the chest.

7. In a piano player, in combination, a 75 tracker board, a casing having a vacuum chest, a power pneumatic, said vacuum chest and power pneumatic being connected by a suitable opening, a single vacuum valve for closing said opening, an outside air 80 valve, said outside air valve being yieldingly held upon its seat when the action is inactive, a secondary pneumatic for holding said outside air valve closed upon the operation of the action, a pneumatic device for 85 operating said vacuum valve and connected with a single opening in the tracker board and varying its operation with the volume of air at the corresponding single opening in the tracker, a primary pneumatic actuated by air from the tracker board for governing the operation of the secondary pneumatic, and means for varying the volume of air admitted to each single opening in 90 the tracker board independently of the 95 vacuum in the chest.

8. In a piano player action, in combination, a power pneumatic, a vacuum chest, said power pneumatic and said chest being connected by a suitable opening, a vacuum 100 valve for closing said opening, an outside air valve arranged between the chest and the power pneumatic, a secondary pneumatic for holding said outside air valve closed, a pneumatic device connected to a 105 single opening in the tracker and opening the vacuum valve varying amounts according to the volume of air admitted at the corresponding single opening in the tracker, means for varying the volume of air admitted at each single opening in the tracker, 110 a suitable bleed between the vacuum chest and said pneumatic device, and means for regulating the flow through said bleed.

9. In a piano player, in combination a 115 tracker board, a power pneumatic, a vacuum chest, said power pneumatic and said chest being connected by a suitable opening, a vacuum valve for closing said opening, an outside air valve arranged between the chest 120 and the power pneumatic, a secondary pneumatic for holding said outside air valve closed, a pneumatic device connected to a single opening in the tracker and opening the vacuum valve varying amounts according to the volume of air admitted at the corresponding single opening in the tracker, means for varying the volume of air admitted at each single opening in the tracker, 125 a suitable bleed between the vacuum chest 130

and said pneumatic device, and an adjusting screw mounted in the chest for regulating the passage through said bleed.

10. In a piano player action, in combination, a casing having an outside air opening and a port leading to the power pneumatic and a suitable vacuum chamber therein communicating with the power pneumatic port, a power pneumatic secured to the casing and having an opening communicating with the power pneumatic port, a valve seat arranged about the opening leading to the vacuum chest, an outside air valve for closing the outside air opening, a stem secured 15 to said outside air valve and projecting into the vacuum chest, means for holding said outside air valve closed during the operation of the action, a sleeve slidably mounted upon said stem, a vacuum valve carried by 20 said sleeve and adapted to engage the seat about the vacuum chest opening, means normally tending to hold said vacuum valve closed, means for opening said vacuum valve, and means for sealing the opening 25 between said sleeve and said stem.

11. In a piano player action, in combination, a casing having an outside air opening, a port leading to the power pneumatic and a suitable vacuum chamber therein communicating with the power pneumatic port, a valve seat arranged about the opening leading to the vacuum chest, an outside air valve for closing the outside air opening, a stem secured to said outside air valve and projecting into the vacuum chest, means for holding said outside air valve closed during the operation of the action, a sleeve slidably mounted upon said stem, a vacuum valve carried by said sleeve and adapted to 30 engage said seat, means normally tending to hold said vacuum valve closed, means for opening said vacuum valve, and a button mounted upon said stem and provided with suitable packing and adapted to be engaged 35 by the end of said sleeve to prevent the passage of air between the sleeve and the stem.

12. In a piano player action, in combination, a casing having a vacuum chamber separated by a partition and provided with 40 a power pneumatic port communicating with the vacuum chamber and an outside air opening through the casing and in alignment with the opening between the power pneumatic port and the chamber with which

it is connected, an outside air valve adapted to close the outside air opening, a stem secured in said outside air valve, means normally tending to hold said outside air valve yieldingly in a closed position, a diaphragm mounted in the casing and adapted 55 when supplied with outside air to hold said outside air valve closed, a sleeve slidably mounted upon said stem, a vacuum valve secured to said sleeve and adapted to close the opening leading from the vacuum 60 chamber to the power pneumatic port, a diaphragm adapted to be operated by outside air for opening said vacuum valve, means for preventing leakage about the valve stem and between it and the sleeve, 65 and a power pneumatic adapted to be controlled by the vacuum valve.

13. In an automatic piano player, the combination of a pneumatic, a tracker board, a pipe communicating therewith, a valve for 70 controlling said pneumatic, and a valve controlling device, comprising two members of different sizes acting in opposition to each other, one side of each member being in communication with the tracker board 75 through said pipe.

14. In an automatic piano player, the combination of a pneumatic, a tracker board, a pipe communicating therewith, a valve for controlling said pneumatic, and a valve 80 controlling device, comprising two members of different sizes acting in opposition to each other, one side of both members being acted upon by the same pressure while the other side of each member is in communication with the tracker board through said 85 pipe.

15. In an automatic piano player, the combination of a pneumatic, a tracker board, a pipe communicating therewith, a valve 90 for controlling said pneumatic, an operating chamber, and a valve controlling device located within said chamber, comprising two members of different sizes acting in opposition to each other, one side of each member being in communication with the tracker board 95 through said pipe.

In testimony whereof I affix my signature in presence of two witnesses.
